[57] CLAIM

The ornamental design for an ashtray for cupholder of vehicles, as shown and described.

DESCRIPTION

FIG. 1 is a perspective view of an ashtray for cupholder of vehicles embodying our new design;

FIG. 2 is a top plan view thereof;

FIG. 3 is a front elevation view thereof, the opposite side being a mirror image thereof;

FIG. 4 is another front elevation view thereof which is similar to FIG. 3, but rotated forty-five degrees, the opposite side being a mirror image thereof; and,

FIG. 5 is a bottom plan view thereof.
